UNITED STATES PATENT OFFICE.

HENRY J. SCHULTE, OF ANAHEIM, CALIFORNIA.

KNOCKDOWN BED.

Application filed April 30, 1924. Serial No. 710,008.

My present invention relates to a knock-down or folding bed capable of being compacted into a comparatively small space, this bed being of the same general type as, 5 and improvement upon, that described and claimed in my co-pending application Serial No. 620,158, entitled as relating to Demountable camp beds, and filed February 20, 1923.

As in the mentioned application, and as 10 in cot beds generally, my knock-down bed may consist essentially of a spring or fabric element, a frame comprising side members and end members to which said spring or fabric element is secured, and supporting 15 legs; and it is an object of this invention to provide simple and effective means enabling the respective side members to be satisfactorily folded and enabling the same to be quickly and reliably connected at will to 20 end members to which the mentioned legs are pivoted in such manner that any weight upon a cot or bed of my improved design must tend to lock or bind the said side members securely in place.

25 It is an object of this invention to provide a simple cot construction comprising end frame members to which legs may be pivotally connected in a manner enabling them to act as levers in the retention of side members, said side members being entirely 30 movable and separately foldable to a length permitting the same to be conveniently disposed within a vehicle or upon a pack animal, the tops of the mentioned legs being 35 so spaced from the substantially horizontal elements of the mentioned end members as to permit of the insertion of the slotted ends of side members therebetween, and the extension of said side members being prefer- 40 ably effective to tension said spring.

45 It is a further object of one embodiment of this invention to provide means permitting the optional use of a removable head or pillow rest of a specific type hereinafter described.

50 Other objects of my invention will appear from the following description of an advantageous embodiment thereof taken in connection with the appended claims and the accompanying drawings, in which

Fig. 1 is a perspective view of a typical embodiment of my present invention.

Fig. 2 is a fragmentary vertical section taken as indicated by the arrow 2 of Fig. 1.

55 Fig. 3 is a similar view taken as indicated by the arrow 3 of Fig. 1.

Fig. 4 is a fragmentary elevational view of an end frame, showing a leg thereof in folded position.

Fig. 5 is a fragmentary bottom plan view 60 showing a preferred hinge construction of the side bars of the bed.

Fig. 6 is a side view of the same.

Fig. 7 is a view of the end of one of the side members showing the slot formed there- 65 in and showing a strut member pivoted thereto.

Fig. 8 is a fragmentary plan view showing members for supporting a pillow rest.

Figs. 9 and 10 are views showing the 70 pillow rest which may be employed with the supporting means shown in Fig. 8.

As shown in Fig. 1 of the drawings, my invention may comprise end members 11 to which legs 12 are pivoted near the ends 75 thereof, as shown at 13. As shown in Figs. 2 and 3, end struts 14 may be pivoted as at 17, to the vertical flanges 16 of the end members 11, and the free ends thereof may be provided with pins 18 arranged to be re- 80 movably extended into holes 19 in the legs 12. Side members 21 extend between the end members 11 and may be of such length as to place the spring fabric 22 under tension, assuming the spring fabric 22 to be 85 secured between the end members 11. The ends of the side members 21, as shown in Fig. 7, are provided with slots 24, which are shown in Fig. 3 so spaced that pins 25, secured in the flanges 26 of the end members 90 11, pass therethrough. The ends of the side members 21 may abut against the vertical flanges of the end members and be held thereagainst by the tension on the fabric 22. As shown in Figs. 4 and 5, side mem- 95 bers 21 may be hinged so that they may be folded into a length which may be substan- tially that of the end members 11. A hinged and somewhat resilient strap 28 is shown as rigidly secured to a section 29 of the side member 21 by means of rivets 30, and as pivoted at its other end to a section 31 by means of a single rivet 32. In order to prevent lateral movement between the sec- 100 tions 29 and 31, a pin 33 is provided, which retains the bar 28 securely against the wall 34 of the member 31. The ends of the bars 29 and 31 are arranged to abut as indicated at 36. Pivoted at 37, as shown in Fig. 1, to the side members 21, I may employ struts 110 or braces 39, which are arranged to be secured to the legs 12 in the same manner.

as the end struts or braces 14. As shown in Fig. 2, the end struts 14 are of such a length as to permit the leg members to move slightly beyond the vertical plane indicated at A—A. That is, the lower ends of the legs 12 are farther apart than the top ends thereof; and from this it will be seen that when a weight is placed upon the bed, there will be a tendency for the lower ends of the legs to swing outwardly as indicated by the arrow 40 in Fig. 2, so that, the legs acting as levers, the upper ends 41 of the legs will be caused to engage the horizontal flange 29 of the side members 21 and grip them rigidly in place. In this manner I may provide very simple means for making rigid connection between the end members 11 and the side members 21.

The bed may be disassembled in the following manner: The end struts 14 may be first disengaged from the leg members 12, as shown in Fig. 2, and allowed to swing into position as indicated at 43. The struts 14 may then be swung into position as indicated at 44 in Fig. 4, and the pin 18 thereof may be placed in a hole 45 and in that manner be retained along the end frame 11. The side struts 39 are similarly removed from place and may assume positions as indicated by the dotted line 47 in Fig. 1. If the legs 12 are then swung to or within the vertical position as indicated by the dotted lines 48 of Fig. 2, it will be seen that this disengages the contact between the upper end 41 and the flange 29 of the side member 21 permitting the latter to be withdrawn. The side members may then be folded, as indicated by the dotted line 50 of Fig. 5, to permit removing the side members from place by reducing tension on the fabric 22. The end members may then be pulled outwardly against the tension on the fabric 23, in a manner to remove the pins 25 from the slots 24. It will be seen that in order for the side members comprising sections 29, 31 to be compactly folded, it is necessary for the member 29 to be moved or sprung laterally, somewhat as shown by the dotted lines 50. This is compensated for by the flexion, as indicated at 51 in the hinge bar or strap 28. Before or after the described movements, leg members 12 of the end frames 11 may be swung as indicated at 52 in Fig. 4. The end frames, the fabric, and the side members may then be rolled into a very compact bundle suitable to be secured to, for example, the running board of an automobile.

If desired, my camp bed may also be provided with a head rest 60, as shown in Figs. 10 and 11. This head rest may optionally be made as an integral casting and it may comprise vertical posts 61 joined together by horizontal rods 62. In the event of the utilization of this head frame 60, it will be

necessary to provide for attaching the same, as by supporting lugs 63, which may be very suitably secured by means of rivets 64 to one of the end frames 11. Openings 65 are shown as provided in each of the lugs 63, through which the reduced cylindrical portions 66, formed on the lower end of the post 61, may extend.

From the foregoing description it will be readily perceived that a bed of this type is suitable for extensive use, as in camping trips, because of the simple construction thereof, because of the sleeping comfort it provides, because of the rigidity thereof when assembled, because of the ease with which it may be assembled or disassembled and because of the compactness thereof when disassembled.

Although I have herein described a preferred embodiment of my invention, it will be understood that various features thereof might be independently employed, and also that various additional modifications might be devised by those skilled in this art, without of the slightest departure from the spirit and scope of my invention, as the same is indicated above and in the following claims.

I claim as my invention:

1. In a knock-down bed, a pair of end members each having a flanged portion and a pair of legs so pivoted thereto as to leave a space between said legs and said flanged portion for the insertion and locking of the ends of removable side members therebetween, and a pair of side members insertable in said space and provided with means for their secure retention against lateral displacement, said retaining means comprising slots in said ends to receive pins projecting downwardly from the flanged portion of said end members.

2. In a knock-down bed: an end member having a vertical wall and a horizontal upper flange; a pair of legs each pivoted at its upper end to said vertical wall below said flange to provide an intermediate space; and removable side members each insertable in one of said intermediate spaces and adapted to be clamped against said flange by the adjacent leg.

3. In a knock-down bed: an end member comprising a transverse angle iron providing a vertical wall and a horizontal flange extending inwardly; and a pair of legs pivoted at their upper ends respectively to opposite end portions of said vertical wall sufficiently below said horizontal flange to leave an intermediate space between said flange and each leg to receive the end of a side member; longitudinal side members insertable respectively in said spaces; means for retaining the side members against lateral displacement, said legs being operable to clamp said side members against the flange of said end member, said retaining means

comprising cooperating slots and projections respectively associated with the end member and the side members.

4. In a knock-down bed comprising side members formed of angle-iron sections, joints in said side members comprising straps rigidly secured to one of said sections, and pivoted to another of said sections, each strap and associated parts being sufficiently resilient to permit said sections to be either positioned end to end or folded one within another.

5. In a knock-down bed comprising side members formed of angle-iron sections,

joints in said side members comprising straps rigidly secured to one of said sections and pivoted to another of said sections, each strap and associated parts being sufficiently resilient to permit said sections to be either positioned end to end or folded one within another, one of said sections being provided with means so engaging a strap pivoted thereto as to force a pair of said sections into substantial alignment.

In testimony whereof, I have hereunto set my hand at Los Angeles, California, this 23rd day of April, 1924.

HENRY J. SCHULTE.
